UNITED STATES PATENT OFFICE.

WILLIAM H. WAY, OF ANKENY, IOWA.

HEN'S NEST.

Application filed June 12, 1922. Serial No. 567,560.

To all whom it may concern:

Be it known that I, WILLIAM H. WAY, a citizen of the United States, and a resident of Ankeny, in the county of Polk and State 5 of Iowa, have invented a certain new and useful Hen's Nest, of which the following is a specification.

The object of my invention is to provide a hen's nest of simple and durable construction.

More particularly, my invention relates to a hen's nest wherein the hen is permitted to enter the nest and after it has entered the nest will be secure against any other 10 hen from entering the nest, while it is laying.

Still another object is to so arrange the structure that after the hen has laid, and desires to leave the nest, the parts will 15 move to position where the closure member will be opened for permitting the hen to leave the nest.

Still another object is to provide a nest 20 preferably made of sheet metal with a screen covering, so that light and air are permitted into the nest and yet the nest is very strong.

Still another object is to provide a hen's nest having a frame member, so that the 25 screen covering for the nest may be removed, when necessary, and a new screen covering installed.

With these and other objects in view, my invention consists in the construction, arrangement and combination of the various 30 parts of my device, whereby the objects contemplated are attained, as hereinafter more fully set forth, pointed out in my claims, and illustrated in the accompanying drawings, in which:

Figure 1 is a perspective view of my improved hen's nest attached to the side of a building.

Figure 2 is a central, sectional view taken 45 through the same, one position being shown in dotted lines; and

Figure 3 is a perspective view showing a portion of the frame and the pivotal connection between the parts.

In the accompanying drawings, I have 50 used the reference numeral 10 to indicate generally a wall of a hen house and 11 the frame structure of my hen's nest.

The frame structure 11 includes a number of bands 12, which are connected together by a cross-piece.

On the upper edge of one of the end bands 12, I place a bracket 13, which is provided with an opening adapted to receive a nail or the like 14, which may be fastened 60 to the wall 10. The nail 14 supports the entire nest structure.

Received within the frame 11 and secured to the iron bands 12 is a screen covering 15. The screen covering 15 is secured to 65 the bands 12 by means of the bolts 16. The screen covering 15 extends substantially half way around the bands 12, as clearly shown in Figure 1 of the drawings.

Received within the frame 11 and the 70 bands 12 thereof is a movable bottom section 17. The bottom section 17 has fixed to it a bar 18, by means of the bolts 19.

The bar 18 is bent downwardly and extends through an enlarged opening 19^a 75 formed in one of the bands 12. The bar 18 is bent so that it is substantially circular in outline and is of spring material. A pin 20 extends through the bar 18 for preventing any sliding movement 80 of the bar within the opening 19^a. The opening 19^a is large enough so as to permit slight pivotal movement of the bar 18 therein.

The bar 18 is so arranged that it places 85 the movable bottom section a slight distance above the band 12 through which it extends. The movable bottom section 17 is provided with a rear wall 21 and a forward wall 22.

The forward wall 22 is not quite so high as the rear wall 21 and is provided with a flange 23 on its upper edge, the purpose of which will be hereafter more fully set forth.

Hingedly secured to the forward end of the frame 11 is the closure member 24 adapted to close the forward end of the

housing section, which is formed by the screen covering 15 and the frame 11.

The bar 18 is so arranged that its forward end rests against the closure member 24. In order to limit the downward movement of the closure member 24, I provide a pair of chains or other suitable flexible elements 25, which are secured to the frame 11 and to the closure member 24.

10 The movable bottom 17 is capable of pivotal movement, the bar 18 serving as a pivot point.

15 The movable bottom section 17 may be provided with straw or other suitable nest material.

19 The movable bottom section 17 may move from the position shown in solid lines in Figure 2 of the drawings to the position shown in dotted lines in the same figure.

20 Assuming now that the parts are in the position shown in dotted lines in Figure 2 of the drawings, and a hen will step upon the closure member 24, which when it is in its down position serves as a support, the 25 hen then passes upon the flange 23 and into the nest material. As soon as the hen has gone in a sufficient amount past the pivot point, the movable bottom member will immediately move to the position shown in 30 solid lines, causing the bar 18 to be moved from the position shown in dotted lines to the position shown in solid lines, bringing the closure member 24 to position where it will partly close one end of the housing section.

35 From the construction of the parts just described, it will be seen that when the parts are in the position shown in Figure 1 of the drawings, it will be impossible for any other 40 hen to go in and disturb the laying hen, and yet the laying hen will receive light and air through the screen covering 15.

45 As soon as the hen desires to leave the nest, it will first walk over to the end of the movable bottom to the closure member 24 and pass its head out through the portion not closed by the closure member 24. The weight of the hen will then cause the movable bottom to assume the position shown in 50 dotted lines in Figure 2, causing the bar 18 to be also moved, due to the fact that it is fixed to the movable bottom.

55 The closure member will then fall to the position shown in dotted lines in Figure 2 and be supported by the chains 25.

60 My improved nest may be used for setting hens and is very efficient.

It will be seen that my hen's nest is very practical and yet is comparatively cheap to build, and is so arranged that it is practically automatic in operation, and when a hen is once within the nest, there is no possibility of its being bothered by any other hen.

Some changes may be made in the con-

struction and arrangement of the various 65 parts of my hen's nest, without departing from the essential features and purposes of my invention, and it is my intention to cover by my claims, any modified forms of structure or use of mechanical equivalents, which 70 may be reasonably included within their scope.

I claim as my invention:

1. A hen's nest of the class described including a housing section, a moving bottom section in said housing section, a closure member hingedly secured to said housing section, a rod mounted on said bottom and extended through said housing section for forming a pivot for said bottom section, the free end of said rod being received against the closure member, whereby movement of said bottom will cause movement of the closure member for the purposes stated.

2. A hen's nest of the class described including a housing section, a moving bottom section in said housing section, a closure member hingedly secured to said housing section, a flexible element for limiting the movement of the closure member in one direction, a rod mounted on said bottom and extended through said housing section for forming a pivot for said bottom section, the free end of said rod being received against the closure member, whereby movement of said bottom will cause movement of the closure member for the purposes stated.

3. A hen's nest of the class described including a screen housing section, a movable bottom section in said housing section, a closure member for partly closing one end of the housing section, flexible elements secured to the housing section and to said closure member for limiting its movement in one direction and for maintaining it in position where it will serve as a support, means operatively connected to the movable bottom section and in engagement with the closure member for operating it, said last means serving as the pivot for the movable bottom section.

4. A hen's nest of the class described including a frame, a screen secured to said frame for forming a housing section, a moving bottom section in said frame, a closure member hingedly secured to said frame, a rod mounted on said bottom and extended through said frame for forming a pivot for said bottom section, the free end of said rod being received against the closure member, whereby movement of said bottom will cause movement of the closure member for the purposes stated.

5. A hen's nest of the class described including a frame, a screen secured to said frame for forming a housing section, a moving bottom section in said frame, a closure

member hingedly secured to said frame, received against the closure member, chains for limiting the movement of said closure member in one direction for permitting it to serve as a support, a rod mounted on said bottom and extended through said frame for forming a pivot for said bottom section, the free end of said rod being

Des Moines, Iowa, June 7, 1922.

WILLIAM H. WAY.
